ATTORNEY.

UNITED STATES PATENT OFFICE

ARTHUR A. GROTHE, OF OAK PARK, ILLINOIS, ASSIGNOR TO WILLIAM J. CAMERON, OF CHICAGO, ILLINOIS

ACTUATING MECHANISM FOR AN ELECTRIC SAFETY RAZOR

Application filed November 18, 1929. Serial No. 407,832.

My present invention relates to safety razors and it has more particular reference to a razor that is provided with means for vibrating the blade holder through the medium of an electric current.

To carry out my invention I have provided a coil having a hollow core in which an armature is placed and caused to oscillate or move rapidly when the current is passing through the coil. The post for carrying the razor or other tool head is mounted in such manner that the rapid movements of the armature are imparted to the tool, or to the cutting edge thereof, mounted in the head. By this action the tool or blade will be given a vibratory movement that is in a direction substantially along the line of its cutting edge. Thus, when a razor blade is secured in the head and is moved across the flesh in a direction transverse to the edge of the blade as is usual when shaving, the blade is vibrated longitudinally of its cutting edge so that there is a shearing or oblique cutting action upon the hair.

The structure which I have devised is made and assembled in a manner so that it provides a handy article and the parts are readily housed within a small handle or grip. While the parts are of small dimensions they are nevertheless simple in construction and possess the quality of sturdiness. The device is novel in construction, is easy to manipulate, and it may be readily taken apart for inspection or repair. I prefer to carry out my invention and to accomplish the objects thereof in substantially the manner hereinafter fully described and as more particularly pointed out in the claims. Reference will now be made to the accompanying drawing that forms a part of this specification.

In the drawing:—

Figure 1 is a view in longitudinal section of my improved safety razor with the handle or housing removed and the tool head omitted.

Figure 2 is a vertical side elevation of the razor operating structure, viewed from the right side of Figure 1.

Figure 3 is a schematic view showing the layout of the electrical parts and circuit.

The drawing is to be understood as more or less schematic for the purpose of illustrating a typical or preferred form in which my invention may be made, and in said drawing I have employed similar reference characters to 55 designate like parts wherever they appear throughout the several views.

In constructing my improved razor I provide a spool of insulating material consisting of a hollow core 5 that is provided with an energizing winding 6, and the lower inner end of the core has a retainer flange 7 that has a transverse aperture 8 for the passage of a conductor 9 leading from the adjacent end of the winding to an iron bar 10 mounted in the 65 bore of the core and projecting beyond the flange 7. The upper or outer end of the core is provided with a plug 11 of greater thickness than the flange 7 and it is screwthreaded upon its exterior so that the structure carried 70 by the spool or core may be readily inserted and screwed into a hollow tubular handle or grip 12 the latter being preferably made of a suitable insulating material such as "bake-lite" or the like. A plug 13, having a central 75 aperture 14, is screwed into the opposite or lower end of the handle or grip as shown in Figure 2.

At its upper or outer end the spool has a yieldable element in the form of a leaf spring 80 15 secured to it by means of screw 16 that passes through one end thereof and enters the plug 11, and said leaf spring extends transversely across the plug so as to bridge the bore of the core. A guide pin 17, projecting from the portion of the plug diametrically opposite the screw 16, enters a hole in the adjacent end of the leaf spring and prevents the latter being moved laterally upon the screw. The spring carries the tool post 85 18 upon which a razor head or other tool is removably mounted, said post being of any desired construction but preferably of the type disclosed in my co-pending application for Letters Patent for a "safety razor structure" filed November 18th, 1929, Serial No. 407,830.

The lower portion of the iron bar 10, where it projects outside the spool, is reduced in dimensions to provide an extension 19 that 100

21 is screwed into the adjacent upper end of a stub 20 projecting upwardly from the base 21 of insulating material. The base, as will be seen, is of disk-like shape and has a recess 5 in its upper face in which a cross plate 22 that carries the post 18 is imbedded or anchored.

22 A pair of irregular or zig-zag shaped terminals 23 and 24 have their outer ends extended through the base 21 into the aperture 14 10 of the lower plug of the handle or grip. The inner end of the terminal 23 is connected by a wire or conductor 25 with an end of the winding or coil 6.

23 An arm 26 of the vibratory type, is mounted upon a screw 27 at the lower portion of the stub and extends up to adjacent the lower end of the iron bar 10. The free end of the arm 26 is in close proximity to the bar 10. In mounting this arm the aperture through 28 which the screw 27 passes is made larger than the diameter of the screw and there is a coil spring 28 interposed between the arm and the screw head and presses against the arm 26 so as to frictionally hold said arm in position and at the same time permit of a yielding vibratory motion of the arm with its lower end as a fulcrum. In order to guide the arm and prevent its transverse movement upon the screw I provide a cross plate 29 at the upper end of the arm, which plate is shaped in cross-section to conform with the circumference of the adjacent portion of the bar 10;—in other words, the plate 29 is bowed or curved.

29 The inner portion of the terminal 24, 35 passes obliquely out of the base 21 so as to escape the head of the screw 27 and upon its inner end the terminal is provided with a spring contact finger 30 that terminates adjacent the upper portion of arm 26 where it 40 has a contact block 31 adapted to engage a similar block upon the adjacent portion of the arm.

30 Within the bore of the core I mount a movable gravity returnable armature 32 in the 45 form of a short rod having buffer pads 33 and 34 upon its respective lower and upper ends. The lower buffer pad 33 maintains the armature out of actual contact with the iron bar 10 and the upper buffer pad 34 is immediately below the spring 15. A surface or coating of insulating material 35 is placed upon the end of the iron bar 10 adjacent the inner end of the armature to prevent arcing between these parts.

35 When the current is switched into the coil 50 the armature 32 is attracted and moves upwardly during each of the rapid energizings of the magnet and between each attraction drops back by gravity and impacts or strikes the insulated end of the iron bar. In moving upwardly the movable armature 32 strikes the spring bridge 15 that carries the tool post 18, the buffer 33 and 34 acting as cushions to prevent the projection of too intense 55 vibration. The vibration or movement of

the armature is very rapid and the impacts are transmitted to the post and thereby imparted to the tool holder or blade carried upon the post so that when a razor blade is used it will be given a movement parallel to its longitudinal cutting edge.

What I claim is:—

1. Actuating mechanism for an electro-safety razor comprising a hollow handle, an electromagnet core mounted therein having a bore and provided with an energizing winding, a longitudinally reciprocatory armature movable in said bore, a spring plate anchored at one end on the end of said core with its free end extending across said bore in position to receive impact from and be vibrated by said armature during reciprocation of the latter, and a tool post having connection with said plate and vibrated during operation of the mechanism.

2. Actuating mechanism for an electro-safety razor comprising a hollow handle, an electromagnet core mounted therein having a bore and provided with an energizing winding, a longitudinally reciprocatory armature movable in said bore, said bore being open at one end, a yieldable bridge anchored at one end and spanning the open end of said bore in position to be engaged by the armature at the outward movement of the latter to laterally vibrate said bridge, and a tool post mounted on said bridge in alinement with said armature whereby said post is vibrated in directions transverse to its axis and the axis of the handle.

Signed at Chicago, Cook County, Illinois, the 21st day of October, 1929.

ARTHUR A. GROTHE.
